UNITED STATES PATENT OFFICE.

GEORGE NEAL PALSER, TIBERIUS MCCALL, AND FRED H. MCCALL, OF
NORTH LOUP, NEBRASKA.

CLAMPING DEVICE.

SPECIFICATION forming part of Letters Patent No. 674,215, dated May 14, 1901.

Application filed December 11, 1900. Serial No. 39,575. (No model.)

To all whom it may concern:

Be it known that we, GEORGE NEAL PALSER, TIBERIUS MCCALL, and FRED H. MCCALL, citizens of the United States, residing at 5 North Loup, in the county of Valley and State of Nebraska, have invented certain new and useful Improvements in Clamping Devices; and we do declare the following to be a full, clear, and exact description of the invention, 10 such as will enable others skilled in the art to which it appertains to make and use the same, reference being had to the accompanying drawings, and to the letters of reference marked thereon, which form a part of this 15 specification.

This invention relates to an improved clamp of that general class employed in connection with Artesian or other wells for temporarily suspending a section of pipe at a desired 20 height therein while another section is being attached thereto or detached therefrom, or for other purposes.

The primary object of the invention is to provide means whereby a section of pipe may 25 be clamped in elevated position and also prevented from turning or rotary movement.

With such object in view the invention contemplates the employment of a primary clamping means adapted to engage a section 30 of pipe longitudinally thereof and a secondary clamping means adapted to engage a section of pipe at substantially the same plane as the primary clamping means, but circumferentially thereof.

35 The invention also relates to improved details and combinations of the several parts, which will herein more fully appear.

In the accompanying drawings an embodiment of the invention is delineated for the 40 purpose of illustration, and in hereinafter referring to the same like reference characters will refer to corresponding parts in both views.

In the drawings, Figure 1 is a side elevational view of the construction, a section of 45 pipe being shown by dotted lines; and Fig. 2 is a plan view thereof.

Referring more specifically to the drawings, A represents a strong base-plate adapted to rest upon the ground or other suitable support, and B a centrally-arranged opening therein through which the pipe is adapted to pass.

Laterally of said opening is a guide-opening C to facilitate the placing of the base-plate in proper position around the pipe. Adapted to clamp the pipe longitudinally thereof 55 is a cam D, serrated or otherwise roughened upon its outer surface, which is pivoted at d and normally held in forward or operative position by the weighted lever E to one side of the plate A. Arranged opposite the biting or clamping edges of the cam aforesaid is a slide-block F, working in the guideway f and provided with an elongated shank f', adapted to be adjusted longitudinally of the opening f² in the base through the medium 65 of an adjusting-screw f³. By reason of this block F being worked back and forth it will be apparent that the size of the opening B through the base may be varied to accommodate various sizes of pipe desired to be operated upon. To limit the forward movement of the cam, a lug or projection d' is formed at its lower end, the lug being designed to contact with a shoulder d² on the base. 70

The portion of the device thus far described 75 will serve to suspend a pipe at the desired height in a well, but will not always be effective in preventing a rotary or turning movement thereof when a section is being screwed to or from the same or otherwise attached in 80 a manner to require a rotary or turning movement, and to accomplish this desideratum the following mechanism is provided: Working in the guideways G on the surface of the base-plate A, near the respective edges thereof, are 85 jaw-carrying members G' G², the former carrying at its end a rigid inclined toothed jaw g and the latter a corresponding toothed jaw g', pivoted at g². The one jaw is pivoted so as to be capable of being swung outwardly 90 (dotted lines, Fig. 2) until the pipe is inserted in the opening B in the base-plate. When the pipe has been inserted, the pivoted jaw is closed, and a projection g³ at the end thereof is engaged by a link or other fastening 95 means g⁴ on the jaw g to prevent the separation of the jaws. A cross-bar h connects the rear ends of the jaw-carrying members, and to the cross-bar a U-shaped lever H is secured at one end and at the opposite end is pivotally 100 connected to a swinging upright H', the upper end of which is in turn connected through

the medium of pivoted links H with the pivoted operating-lever I. It will thus be seen that as the operating-lever I is pulled backward the pivoted links will correspondingly 5 operate the upright, and by reason of the U-shaped lever the jaws will be caused to bind the pipe circumferentially and prevent the same from turning. A forward movement of the lever will manipulate the several parts in 10 a manner opposite that just described. Some means must be provided for locking the jaws against movement when in clamping position, so we provide at the upper end of the swinging upright a projection or tooth l, which 15 is adapted to be engaged by the teeth of the gravity-catch L, pivoted at l' to the base-plate and normally inclined forwardly and held in operative position by its own weight.

Many changes or alterations of the several 20 parts and arrangement of parts in the construction just described may be readily made without departing from the spirit of the invention.

Having thus described the invention, what 25 is claimed as new, and desired to be secured by Letters Patent, is—

1. A clamping device comprising a base pro-

vided with a through-opening, gripping means 30 slideable on the base and means for actuating the gripping means comprising a main pivoted operating-lever, a pivoted upright, connections between the lever and upright and connections between the upright and the gripping means, substantially as described.

2. A clamp comprising a base provided with 35 a through-opening, a gripping means, an opposing gripping means slideable back and forth on said base, and means for actuating said opposing gripping means comprising a main pivoted operating-lever, a swinging upright, 40 connections between the upright and lever, connections between the upright and the gripping means, a lug or projection on the swinging upright, and a catch adapted to engage the lug or projection to lock the parts in ad- 45 justed position, substantially as described.

In testimony whereof we affix our signatures in presence of two witnesses.
